LIQUOR DISPENSER

David R. Jones, R.R. 4, Box 21B, Little Cub Road,
Evergreen, Colo. 80439

Filed Sept. 7, 1973, Ser. No. 395,356

Term of patent 14 years

Int. Cl. D15—08

U.S. Cl. D94—3 B

Fig. 1

Fig. 4

Fig. 5

Fig. 2

Fig. 3

Fig. 6

Fig. 7

FIG. 1 is a left side front perspective view of a liquor dispenser showing my new design;

FIG. 2 is a front view thereof in elevation;

FIG. 3 is a right side view thereof in elevation with the left side view being a mirror image thereof;

FIG. 4 is a rear elevational view thereof;

FIG. 5 is a top plan view thereof with the bottom plan view being a mirror image thereof;

FIG. 6 is a front perspective view on an enlarged scale, the door being in an open position to disclose the interior thereof; and

FIG. 7 is a right side front perspective view thereof. The broken line showing of the liquor bottles in FIG.

6 is for illustrative purposes only. The left interior of the liquor dispenser in open position is plain except for the latches.

I claim:

The ornamental design for a liquor dispenser, as shown and described.
